JOURNAL BOX CONSTRUCTION FOR RAILWAY CARS

Theodore J. Sweger, Naperville, Ill., assignor to Illinois Railway Equipment Company, Chicago, Ill., a corporation of Illinois

Filed Mar. 11, 1964, Ser. No. 351,026
13 Claims. (Cl. 308—40)

This invention relates, generally, to railway car journal boxes and it has particular relation to axle journal guides therefor. It constitutes an improvement over the construction shown in application Serial No. 325,887, filed November 26, 1963.

Among the objects of this invention are: To arrange and construct the spring wire frame holding journal guides between diametrically opposite sides of an axle journal and the adjacent side walls of a journal box in such manner that the assembly can be readily inserted in the journal box or removed therefrom with the axle journal remaining therein; to form the rear section of the spring wire frame with 180° bends providing bights for engaging a dust guard wall and with a central portion extending parallel to the dust guard wall and a plane containing the sides of the journal brass stop columns facing the dust guard wall; to form each journal guide with a bearing section and a support between which portions of the spring wire frame extend for holding the journal guides in operative position in the journal box and on opposite sides to the axle journal; to provide the bearing section with deformable extensions projecting through openings in the support and headed over to form therewith a unitary construction; to form an inverted T-shaped groove between the bearing section and the support for receiving the inverted T-shaped ends of the front and rear sections of the spring wire frame; to form the inverted T-shaped groove entirely in the support; to extend the end portions of the front and rear sections of the spring wire frame beyond the upper end of the respective stem of the groove and away from the axle journal into underlying relation with the lower curved end of the journal brass stop column on the adjacent side wall of the journal box; and to construct the support and bearing section forming each journal guide in a generally truncated pyramidal configuration.

In the drawings:

FIG. 1 is a vertical sectional view taken generally along the line 1—1 of FIG. 3 and showing both sides of the journal box and omitting the adjusting shim.

FIG. 2 is a vertical sectional view taken generally along the line 2—2 of FIG. 1, the axle, journal brass and wedge being shown in broken line outline in order to depict more clearly the details of construction of the one piece spring wire frame which supports the journal guides.

FIG. 3 is a horizontal sectional view taken generally along the line 3—3 of FIG. 2.

FIG. 4 is a view, in front elevation, of the support which forms a part of each journal guide.

FIG. 5 is a horizontal sectional view taken generally along the line 5—5 of FIG. 4.

FIG. 6 is a vertical sectional view taken generally along the line 6—6 of FIG. 4.

FIG. 7 is a view, in rear elevation of the support shown in FIG. 4.

FIG. 8 is a view, in front elevation, of the bearing section which forms a part of the journal guide and is arranged to be mounted on the support shown in FIGS. 4—7.

FIG. 9 is a top plan view of the bearing section shown in FIG. 8.

2

FIG. 10 is a view, in end elevation, of the bearing section shown in FIG. 8.

Referring now particularly to FIGS. 1, 2 and 3 of the drawings, it will be observed that the reference character 10 designates, generally, a railway car axle which, in FIGS. 2 and 3, is shown in broken line outline in order to illustrate more clearly the details of construction of the journal guides and support therefor. The railway car axle 10 includes an axle journal 11 provided with an end collar 12 and it is arranged to rotate about an axis of rotation or its longitudinal axis which is indicated at 13. The axle journal 11 is mounted within a railway car journal box, indicated generally at 14, which is of conventional construction. The railway car journal box 14 includes a horizontal top wall 15 from which vertical side walls 16—16 depend. They are interconnected at their lower ends by a bottom wall 17 which has a concave inner surface 18. This may be a cylindrical surface. The concave inner surface 18 of the bottom wall 17 terminates at its forward end, FIG. 2, in a concave inner surface 19 on the inner side of an end wall 20 which is located below a lid opening 21 (the lid not being shown). The rear end of the concave inner surface 18 of the bottom wall 17 terminates in a vertical wall 22 of a dust guard well 23 which is completed by a vertical wall 24. Formed integrally with the depending vertical side walls 16—16 are journal brass stop columns 25—25 having concave surfaces 26—26 at their lower ends. The journal brass stop columns 25—25 serve to guide ends 27—27 of a journal brass or bearing 28 which is arranged to engage the surface of the axle journal 11. The journal brass or bearing 28 is surmounted by a wedge 29 which, together with the journal brass or bearing 28, is held in position by a wedge stop 30 that depends from the under surface of the top wall 15 adjacent the lid opening 21.

With a view to limiting the relative movement of the axle journal 11 and the railway car journal box 14 when the railway car is accelerating or decelerating, journal guides 33—33 are provided. The journal guides 33—33 are positioned between the inner sides 16—16 of the journal box 14 and diametrically opposite sides of the axle journal 11 symmetrically with respect to a horizontal plane through the longitudinal axis 13. Preferably the journal guides 33—33 are of identical generally truncated pyramidal configuration. They are mounted in a manner to be described such that they are held in operative position as shown in FIGS. 1, 2 and 3 of the drawings in such manner that they can be readily inserted in the railway car journal box 14 or removed therefrom with the axle journal 11 therein. In order to apply or remove the journal guides 33—33 the journal box 14 is jacked upwardly to permit removal of the wedge 29 and journal brass or bearing 28.

Each of the journal guides 33 includes a bearing section that is indicated, generally, at 34 in FIGS. 8, 9 and 10 of the drawings. The bearing section 34 is formed of forged bearing alloy composed principally of copper and zinc with small amounts of manganese, aluminum and silicon. The bearing section 34 has a planar front face 35 which is located, as shown in FIG. 1, in a vertical plane in spaced relation to the surface of the axle journal 11. The bearing section 34 is oblong in configuration and tapers outwardly from the front face 35. It has semi-circular ends 36—36 and a planar rear face 37 from which tapered deformable extensions 38—38 project. Preferably the extensions 38—38 are located substantially equidistant from the ends of the bearing section 34 and equidistant from its center. Also they are located along the longitudinal axis thereof.

Each bearing section 34 is arranged to be mounted on

a support that is shown, generally, at 41 in FIGS. 4 to 7 inclusive. The support 41 preferably is formed of drop forged steel, is oblong in configuration, and has a planar front face 42 from which the outer surface tapers outwardly. The bearing section 34 in operative position has its planar rear face 37 juxtaposed to the planar front face 42 of the support 41. When thus assembled they form the truncated pyramidal configuration above referred to. Openings 43—43 are provided through the support 41 for receiving the extensions 38—38 from the bearing section 34. Recesses 44—44 are provided in communication with the openings 43—43 in which the extensions 38—38 can be headed over as indicated at 45—45 in FIGS. 1 and 3 of the drawings. The support 41 has a rear face 46 the upper portion of which is curved to conform to the curvature of the surfaces 26—26 at the lower ends of the journal brass stop columns 25—25.

Depending upon the diameter of the axle journal 11, the journal guides 33—33 can be employed, as shown in FIG. 1. Alternatively, when the diameter of the axle journal 11 is somewhat reduced, it is desirable to space the journal guides 33—33 slightly from the inner surfaces of the vertical sides 16—16 of the journal box 14. For this purpose, as shown in FIGS. 2 and 3, a shim 47 is provided, one for each journal guide 33. The shim 47 is inserted between the rear face 46 of the support 41 and the adjacent surface of the vertical sides 16. It is generally rectangular in configuration and conforms to the configuration of the rear face 46 of the support 41. Ears 48, located at the corners of the shim 47, are arranged to be deformed against the face of the support 41. If it is unnecessary to use the shims 47 because of the diameter of the axle journal 11, they can be removed readily.

With a view to mounting each journal guide 33 in operative position as shown in FIGS. 1, 2 and 3 an inverted T-shaped groove is provided between the bearing section 34 and the support 41. The T-shaped groove, in the embodiment shown, is formed in the support 41 and comprises a horizontally extending bar portion 49 and an upwardly extending stem portion 50 the width of which is twice that of the bar portion 49. While the T-shaped groove formed by the bar portion 49 and stem portion 50 is shown as being provided in the planar front face 42 of the support 41, it will be understood that such a groove can be formed in the planar rear face 37 of the bearing section 34 or it can be formed partly in the support 41 and partly in the bearing section 34. The particular location of the inverted T-shaped groove depends, in part, on the required thickness of the bearing section 34. It can have maximum thickness, as shown, if the inverted T-shaped groove is formed wholly in the support 41.

For holding the journal guides 33—33 in operative position in the railway car journal box 14 a unitary spring wire frame, shown generally at 53, is provided. It includes a front section, shown generally at 54, and a rear section, shown generally at 55. The front section 54 has a central portion 56 which extends from the journal guides 33—33 downwardly and forwardly and conforms generally in curvature to the curvature of the inner surface 18 of the bottom wall 17. The rear section 55 has a central portion 57 which is located generally parallel to and spaced forwardly from the vertical wall 22 and adjacent a vertical plane in which are located the walls 58 of the journal brass stop columns 25—25 that face the vertical wall 22. The central portion 57 is located in the position described by providing a 180° bend 59 in the rear section 55 having lower and upper arms 60 and 61 that extend parallel to each other and adjacent the respective sides 16—16 of the journal box 14. The bight 62 formed by this configuration is arranged to bear against the outer side of the vertical wall 22 of the dust guard well 23 and thus serves to limit the inward movement of the journal guides 33—33 and to hold them against further inward movement in the railway car journal box 14. The front and rear sections 54 and 55 of the unitary spring wire

frame 53 are provided with inwardly extending portions 64 and 65 from which lateral portions 66 and 67 extend into the bar portion 49 of the inverted T-shaped groove that is formed in the support 41 on each side of the axle journal 11. Upstanding end portions 68 and 69 from the juxtaposed ends of the lateral portions 66 and 67 extend through the stem portion 50 of the inverted T-shaped groove in each support 41. The terminal portions 70 and 71 of the end portions 68 and 69, as shown in FIG. 1, extend outwardly in underlying relation to the concave surfaces 26—26 at the lower ends of the journal brass stop columns 25—25. In this position these terminal end portions 70—70 in cooperation with the concave surfaces 26—26 limit upward movement of the journal guides 33—33.

A position tag 72 is located on the center of the central portion 56 of the front section 54 in order to indicate that, in the assembled position, it is to be located in the front portion of the railway car journal box 14.

In order to assemble the unitary spring wire frame 53 with the journal guides 33—33, the upstanding end portions 68 and 69 are located in the stem portion 50 of the inverted T-shaped groove in the supports 41. Then the bearing sections 34 are applied with the deformable extensions 38—38 extending in telescoped relation through the openings 43—43. Thereafter the portions of the extensions 38—38 in the recesses 44—44 of the supports 41 are headed over, as indicated at 45—45. Not only does this provide a unitary construction for the spring wire frame 53, since the ends thereof are securely clamped between the supports 41 and the bearing sections 34 of the journal guides 33—33 but also the journal guides 33—33 themselves are securely clamped in position. At the same time a relatively large bearing surface is provided by the planar front faces 35 of the bearing sections 34 on diametrically opposite sides of the axle journal 11.

What is claimed as new is:

1. In combination:

(a) a railway car journal box having a bottom wall interconnecting its side walls from which journal brass stop columns extend toward each other, a dust guard wall at its inner end, and an axle journal spaced from said side walls,

(b) journal guide means on diametrically opposite sides of said axle journal between it and the respective side wall, and

(c) a unitary spring wire frame supporting said journal guide means in operative position in said journal box including:

(1) front and rear sections engaging said bottom wall,

(2) lateral portions between the upper ends of said front and rear sections supporting said journal guide means, and

(3) shoulder portions formed by 180° bends interconnecting said rear section and the lateral portions individual thereto with the bights reacting against said dust guard wall,

(4) the central portion of said rear section being spaced outwardly from said dust guard wall.

2. The invention, as set forth in claim 1, wherein the central portion of the rear section of the unitary spring wire frame is generally parallel to the dust guard wall and juxtaposed to a plane containing the sides of the brass stop columns facing said dust guard wall.

3. In combination:

(a) a railway car journal box and an axle journal therein between the side walls thereof,

(b) journal guide means on diametrically opposite sides of said axle journal between it and the respective side wall each including:

(1) a bearing section carrying a front face juxtaposed to said axle journal and having on the opposite face at least one deformable extension, and

- (2) a support carrying a rear face reacting against the respective side wall and telescoped over said extension which is deformed to provide with said bearing section a unitary construction; and
 (c) a unitary spring wire frame having portions extending between the bearing sections and the supports of said journal guide means for holding them in operative position in said journal box.

4. The invention, as set forth in claim 3, wherein:

- (a) each bearing section has two deformable extensions telescoped with the respective support, and
 (b) the portions of the spring wire frame extend through each journal guide means between the two extensions of the bearing sections.

5. In combination:

- (a) a railway car journal box and an axle journal therein between the side walls thereof,
 (b) journal guide means on diametrically opposite sides of said axle journal between it and the respective side wall each including:

- (1) a bearing section carrying a front face juxtaposed to said axle journal and having on the opposite face at least one deformable extension, and
 (2) a support carrying a rear face reacting against the respective side wall and telescoped over said extension which is deformed to provide with said bearing section a unitary construction,
 (3) there being a wire receiving groove between said bearing section and said support; and
 (c) a unitary spring wire frame having portions extending into the grooves between the bearing sections and the respective supports for holding said journal guide means in operative position in said journal box.

6. The invention, as set forth in claim 5, wherein:

- (a) each bearing section has two deformable extensions telescoped with the respective support,
 (b) the groove is located in each support and is of inverted T-shape, and
 (c) end portions of front and rear sections of the spring wire frame extend through the ends of the bar portions of each T-shape and commonly through the stem portion of each T-shape.

7. The invention, as set forth in claim 6, wherein the terminal portions of the front and rear sections of the spring wire frame extend beyond the upper end of the respective stem portion of the groove in the support and away from the axle journal into underlying relation with a journal brass stop column on the adjacent side wall of the journal box.

8. The invention, as set forth in claim 5, wherein a shim is interposed between each support and the juxtaposed side wall of the journal box.

9. The invention, as set forth in claim 6, wherein:

- (a) each journal guide means is of generally truncated pyramidal configuration,
 (b) the support is generally oblong,
 (c) the ends of the bearing section are semi-circular,
 (d) the deformable extensions are located along the longitudinal axis of the bearing section equidistant from its ends and center, and
 (e) the side of the support facing the adjacent side wall of the journal box is recessed to receive the deformed portions of said extensions.

10. Journal guide means for positioning between a side wall of a journal box and an axle journal and arranged to be held in operative position by end portions of a spring wire frame arranged in inverted T-shape comprising:

- (a) a bearing section carrying a front face for juxtaposition to said axle journal and having a pair of deformable extensions on the opposite side, and
 (b) a support for said bearing section having apertures for receiving said deformable extensions, a rear face for reacting against said side wall and recessed to receive the deformed portions of said extensions, and a front face juxtaposed to the rear face of said bearing section,
 (c) there being an inverted T-shaped groove between said bearing section and said support for receiving said end portions of said spring wire frame.

11. The invention, as set forth in claim 10, wherein the inverted T-shaped groove is located in the front face of the support.

12. The invention, as set forth in claim 10, wherein:

- (a) the journal guide means is of generally truncated pyramidal configuration,
 (b) the support is generally oblong,
 (c) the ends of the bearing section are semi-circular, and
 (d) the deformable extensions are located along the longitudinal axis of the bearing section equidistant from its ends and center.

13. The invention, as set forth in claim 12, wherein the inverted T-shaped groove is located in the front face of the support between the extensions from the bearing section.
